CIRCUITS FOR TRACER CONTROLLED
MACHINE TOOLSJacob J. Jaeger, West Hartford, Conn., assignor
to Niles-Bement-Pond Company, West Hart-
ford, Conn., a corporation of New Jersey

Application June 28, 1943, Serial No. 492,543

4 Claims. (Cl. 192—84)

1

This invention relates to tracer controlled electrically operated machine tools and particularly to improved operating means for the clutch magnets of a form turning lathe, copying milling machine, or similar machine tool.

A primary object of the invention is to provide improved circuits controlling the energization of clutch operating electromagnets so that their speed of operation in starting and stopping movements of machine slides controlled thereby may be increased.

A feature of importance of the invention is that the clutch magnets are initially energized with a high potential and thereafter the potential is substantially reduced, the potential remaining after this reduction being sufficient to hold the clutch engaged so that movement of the slide operated thereby may be continued, and, when the reduced potential circuit for a clutch magnet is opened to release the clutch, the time of release of the clutch is substantially decreased to stop further movement of said slide and prevent overtravel.

Another feature of importance is that the clutch magnet energizing circuits are controlled through relays, one of which serves to energize a magnet with full line potential; and a second relay, operated momentarily after the first relay, controls the holding circuit for the clutch magnet at a reduced potential.

The invention has been illustrated as embodied in a machine of the type shown and described in the patent to Shaw 1,711,290, granted April 30, 1929, and the present invention will be described in connection with the circuits shown in that patent for controlling movements of a tool carriage and cross slide. It will be understood, however, that the invention may be employed in other types of machine tools in which movements of the tool relative to the work are controlled by a contact closing tracer following a pattern or template and in which the means for moving the tool include rotating clutch magnets coupled when energized as indicated in the above-referred to patent to drive lead screws or other actuating means for the movable slides of the machine.

In general, therefore, it is a primary object of the present invention to increase the speed of operation of clutch magnets controlling movements of machine tool slides by reducing the holding voltage of its coil after initially energizing the coil with full potential, the energizing potential causing extremely rapid engagement of a clutch and the reduced holding voltage being sufficient, after the clutch has been engaged, to continue to hold the clutch engaged under any load that may

2

be initially started by the clutch at full potential.

Other objects and advantages will be apparent from the specification and claims, and from the drawings, which illustrate what is now considered to be a preferred embodiment of the invention.

In the drawings annexed hereto and forming a part of this specification:

Figure 1 is a front elevation of an engine lathe to which the present invention may be applied, parts being shown in section to more clearly show their construction.

Fig. 2 is a plan view of the machine shown in Fig. 1, several parts being shown in section.

Fig. 3 is a fragmentary cross-sectional view of the machine shown in Figs. 1 and 2, and

Fig. 4 is a diagram of the electric circuits for the clutch operating magnets.

In its preferred form, the invention may include the following principal parts: First, a machine tool such as an engine lathe shown in the drawings as having tool slides mounted one on the other for movements at right angles to each other; second, magnetic clutches for actuating each of the slides in either direction; third, a pattern or template supported in fixed position on the machine; fourth, a tracer movable with said slides over a surface of said pattern or template; fifth, relays operated by contacts on said tracer controlling circuits for said clutches; sixth, a supplemental relay controlled by operation of either of the first mentioned relays so that the supplemental relay operates after either of said first relays operates; and seventh, supplemental clutch magnet circuits having a reduced potential compared to the first clutch magnet circuits, said supplemental magnet circuits being controlled by said supplemental relay.

Referring more in particular to the figures of the drawing, the lathe comprises the usual bed 1 having a headstock 2 at one end within which is mounted a work rotating spindle 3. A carriage 6 is provided which may be moved to the left or right along the bed 1 by means of a suitable lead screw 7. Lead screw 7 is connected through suitable driving connections to magnetic clutches 10 similar in every way to those shown in the above-mentioned patent and therethrough to spindle 3 so that when one electromagnet is energized the carriage 6 will be moved in one direction along the lathe bed and when the opposite magnet is energized the carriage will be moved in the opposite direction. It will thus be seen that by simply energizing one clutch magnet or the other, movements of the carriage 6 may be reversed, or,

by breaking a clutch magnet circuit, movement of the carriage 6 will be stopped.

The carriage 6 is provided with a cross slide 17 carrying a tool holder 18 and is adapted to be operated to move the tool 19 directly toward or from the work. To effect movement of this cross or tool carrying slide 17 there is provided a transverse lead screw 20. The cross feed screw 20 may be manually operated in the usual manner and, in addition is connected by means of bevel gears 22 to a shaft 23 adapted to be driven by either of a pair of magnetic clutches 12 provided in a suitable clutch housing 24 supported upon the tool carriage 6 so as to travel therewith. The two clutches 12 in the housing 24 are similar to clutches 10 for longitudinally moving the carriage 6 so that when one clutch 12 is energized the tool moves "in" and when the other clutch 12 is energized the tool moves "out." The work being turned may be held between centers in the usual manner and may be rotated at any desired speed, movement of the carriage 6 by lead screw 1 driven from the spindle 3 through clutches 10 being at all times proportionate to the rotation of the work.

The cross slide 17 is provided with a bracket or arm 30 the outer end of which supports a contact tracer 31, the tracer point 32 of which is adapted to engage a pattern or template 33 corresponding in outline to the work being operated on. The pattern or template 33 is mounted in fixed position and may be directly supported on a suitable bracket 34 secured to the lathe bed 1. Thus it will be seen that by having the tracer 31 follow the pattern and by having tracer 31 control the movements of the respective lead screws 7 and 20 through the magnetic clutches 10 and 12 the cross slide and the lathe tool will be moved toward or from the axis of the work during traversing movement of the slide 6 to the left or right along the lathe bed 1 and will reproduce the form or outline of the template thereon. In this mechanism the tracer 31 controls the "in" and "out" movement of the lathe tool by controlling circuits for the magnetic clutches 12 operating the transverse screw 20, and when movement of the tool 19 in or out occurs the traversing movement of slide 6 is interrupted. This control of the magnetic clutches through the tracer 31 will be further referred to in connection with the wiring diagram.

The magnetic clutches 10 for operating the longitudinal lead screw 7 are indicated in the wiring diagram, Fig. 4, as "E" and "W," and the magnetic clutches 12 for operating the transverse screw 20 are indicated respectively by "in" and "out." The tracer 31 is indicated diagrammatically and may be similar to that shown in patent to J. C. Shaw 1,518,114, granted December 2, 1924. The tracer and tracer point form no part of the present invention and will be referred to only briefly.

The tracer point 32 is adapted to actuate the contact carrying lever 39 pivotally mounted within the head of the tracer body 31 whenever the tracer point touches the work. This lever carries a contact 42 cooperating with an adjustable contact 43 at the end of an insulated screw in the bracket plate 46 supported on the tracer body 31. The tracer body 31 is grounded, as indicated, so that an electric circuit may be completed through the contacts 42-43 and lever 39. A tension spring 48 and a compression spring 49 are adapted to draw the upper end of the lever outward to normally hold the "in" contacts

42-43 closed. Normally, the tool 19 travels "in" or toward the work until the tracer point 32 also moving "in" therewith is tilted by contact with the pattern.

5 The pivotally mounted lever 39 also carries a contact 50 on the opposite side from contact 42 which is adapted to cooperate with an adjustable contact 51 on an adjusting screw 52 suitably insulated and mounted on a lever 54 pivoted to the tracer body 31 but insulated completely therefrom. A compression spring and suitable adjusting screws are provided for holding the lever 54 toward the upper end of the first mentioned lever 39, but the forward or normal position of this auxiliary lever 54 is limited by an adjusting screw 59, the end of which carries a contact 60 cooperating with a contact 61 on the upper end of the lever 54. The adjusting contact screw 59 is as shown insulated and is mounted in the bracket plate 46.

20 It will be seen from the wiring diagram that the normally closed circuit through contacts 42-43 energizes the solenoid of the triple pole "in" relay, which is shown unenergized. This circuit from the grounded tracer extends through 25 lever 39, contacts 42-43, lead 63, the "in" relay, and lead 67 to a grounded generator 68. Energizing of the "in" relay simultaneously closes two 30 circuits and opens a third circuit. The opened circuit extends from line wire 70 to the contactor 71, lead 73, tracer contacts 60-61, lead 74 to one or the other of "E" "W" clutches, whichever is being used, and lead 75 to line wire 76. As soon, therefore, as "in" relay is energized, 35 movement of the carriage 6 stops.

40 Closing of contactor 71 by the energized "in" relay starts the tool 19 moving toward the work, this circuit from line wire 70 includes lead 78, contactor 71, lead 79 to the "in" clutch, and lead 80 directly to the line wire 76. Closing of contactor 81 by the "in" relay energizes a supplemental relay 82 and the energizing of this relay 45 involves a slight lapse of time following the closing of contactor 81, this circuit including grounded generator 68, lead 67, contactor 81, lead 83 to relay 82 to ground. The function of supplemental relay 82 which is shown de-energized, will presently be described.

50 When the tracer point 32 strikes the pattern, contacts 42-43 are opened; this will de-energize the "in" relay. De-energizing the "in" relay into the position shown in Fig. 4 opens the circuit to the "in" clutch, opens the circuit to the supplemental relay 82 and simultaneously closes the circuit to the "E" or "W" clutch, whichever has been selected by the manual switch 92.

55 The carriage will then move along the bed 1 until the shape of the pattern or template causes the tracer point 32 to move a sufficient distance to close either the contacts 42-43 if the pressure is eased, or the contacts 50-51 if the pressure is increased. Closing the contacts 42-43 will repeat the operation described above. Closing the contacts 50-51 will energize the "out" relay, the circuit including the grounded tracer 31, lever 39, contacts 50-51, lead 85, "out" relay, lead 67, and the grounded generator 68.

60 Energizing the "out" relay closes the circuit to the "out" clutch, closes the circuit to the supplemental relay 82, and simultaneously opens the circuit to the "E" or "W" clutch.

65 From the above it will be seen that closing tracer contacts 42-43 or 50-51 causes the operation of the supplemental relay 82, and, as the circuit for operating this supplemental relay in-

cludes contacts controlled by the "in" or "out" relay, relay 82 is not energized until after the "in" or "out" relay has been energized. Supplemental relay 82, when energized, opens one normally closed contact and closes another contactor which is normally open.

A moment after the "in" or "out" relay, which constitute individual principal electrical means for the clutches, is energized the supplemental relay 82 is energized and opens the circuit from line wire 76 through contact 87 to the lead 80. With contact 87 open, the circuit from line wire 76 to lead 80 must traverse resistance 88, thus reducing the potential applied to hold the "in" or "out" clutch, whichever is operating. Energizing relay 82 also closes contact 90 and cuts out resistance 91 from the circuit to the "E" or "W" clutch magnet so that when one of these latter magnets is again energized it will be at the full potential of the line. This energizing at full potential continues momentarily after the "in" or "out" relay opens, as supplemental relay 82 cannot release until after the "in" or "out" relay releases. As soon as supplemental relay 82 has been de-energized, contact 90 will open and resistance 91 will then be included in the "E" or "W" clutch magnet circuit, so that these clutches are initially energized with the full potential of the line and are held in engagement with a reduced potential similar to the "in" and "out" clutches.

It will be seen that a manual selector switch 92 enables the "E" or "W" clutch to be used for the normal or leading movement of the tool along the lathe bed 1.

What I claim is:

1. In a device controlled by a plurality of electromagnetic clutches, principal electrical means for each of said electromagnetic clutches connected for applying thereto a predetermined initial voltage, individual control means for controlling such application of each of said electrical means, and a single supplemental time delay electrical means connected to both of said principal electrical means adapted to substantially reduce the magnitude of the voltage maintained applied by said one principal electrical means to its clutch a predetermined time after the application thereto of said initial voltage independent of other conditions, whereby pick-up time and releasing time and overtravel are reduced.

2. In a device controlled by a plurality of electromagnetic clutches, principal electrical means for each of said electromagnetic clutches connected for applying thereto a predetermined initial voltage, individual control means for controlling such application of each of said electrical means, and supplemental time delay electrical means connected respectively to both of said principal electrical means adapted to substantially reduce the magnitude of the voltage maintained applied respectively by each of said two electrical means to its respective clutch a predetermined time after the application to the respective clutch of said initial voltage independ-

ent of other conditions, whereby pick-up time and releasing time and overtravel are reduced.

3. In a device controlled by a plurality of electromagnetic clutches, principal electrical means for each of said electromagnetic clutches connected for applying thereto a predetermined initial voltage, individual control means for controlling such application of each of said electrical means, and supplemental time delay electrical means connected to both of said principal electrical means adapted to substantially reduce the magnitude of the voltage maintained applied by said one principal electrical means to its clutch a predetermined time after the application thereto of said initial voltage independent of other conditions, said supplemental means being actuatable by said individual control means through the said principal electrical means, whereby pick-up time and releasing time and overtravel are reduced.

4. In a device controlled by a plurality of electromagnetic clutches, a source of electrical power, principal relay means having a first set of controlled contacts connected between said source and said one clutch, said relay means further having a second set of controlled contacts connected between said source and another clutch, said relay means and its connections being adapted to selectively complete connections from said clutches to either of said sets of contacts but not to both, supplemental relay means connected for actuation a predetermined time after the actuation of said principal relay means independent of other conditions and having controlled contacts, individual resistors for the energizing circuits of each of said clutches respectively, connections between said resistors respectively and said controlled contacts of said supplemental relay means and the energizing circuits of said clutches for respectively inserting each of said resistors in series in the energizing circuit of each of said clutches respectively upon energization or de-energization of said supplemental relay means after said predetermined time delay, and switch means connected to actuate said principal relay means.
